UNITED STATES PATENT OFFICE.

WILLIAM B. SPROUL, OF LANSFORD, PENNSYLVANIA.

BRAKE-SHOE.

1,355,708.

Specification of Letters Patent.

Patented Oct. 12, 1920.

Application filed January 3, 1920. Serial No. 349,195.

To all whom it may concern:

Be it known that I, WILLIAM B. SPROUL, a citizen of the United States, residing at Lansford, in the county of Carbon and 5 State of Pennsylvania, have invented certain new and useful Improvements in Brake-Shoes; and I do hereby declare the following to be a full, clear, and exact description of the invention, such as will enable others skilled in the art to which it appertains to make and use the same.

This invention relates to new and useful improvements in braking devices for railway cars and has for its primary object the 15 provision of means whereby a pair of wheels of a car can be held against rotation thereby retarding the descent of a car on a steep grade or hill and also will prevent the non-rotating wheels from contacting or sliding 20 on the rails of the track, thus obviating wear to the wheels and the liability of them becoming flat.

Another object of this invention is the provision of brake shoes adapted to operate 25 in pairs and which can be easily and conveniently applied to the wheels and rails of the track and when applied or in use will prevent the wheels to which they are applied from coming out of alinement with 30 the rails of the track thus preventing the car from jumping the track.

A further object of this invention is the provision of a brake shoe of the above stated character, which shall be simple, durable, 35 and efficient, and which may be manufactured and sold at a comparatively low cost.

With these and other objects in view as will become more apparent as the description proceeds, the invention consists in certain 40 novel features of construction, combination, and arrangement of parts as will be hereinafter more fully described and claimed.

For a complete understanding of my invention, reference is to be had to the following description and accompanying drawings, in which:

Figure 1 is a perspective view of a railway car illustrating brake shoes applied to

a pair of wheels thereof and which are constructed in accordance with my invention,

Fig. 2 is a side elevation of one of the brake shoes,

Fig. 3 is a plan view of the same,

Fig. 4 is a rear elevation illustrating the 55 inclination of the rear end of the shoe.

Fig. 5 is a transverse sectional view taken on the line 5—5 of Fig. 2, and

Fig. 6 is a similar view taken on the line 60 6—6 of Fig. 2.

Referring in detail to the drawings, the numerals 1 and 2 indicate brake shoes adapted to be positioned upon the rails 3 of a track 4 with a pair of wheels 5 of a railway car 6 thereon so that the rotation 65 of said wheels is prevented thereby retarding the speed of the car on a steep grade or hill and also preventing the non-rotating wheels from contacting or sliding on the rails 3 of the track 4 which prevents the 70 wheels from wearing or becoming flat. The brake shoes 1 and 2 are identical in construction, and reference to one in detail is thought to be sufficient for both.

The brake shoe consists of a base 7 which 75 has formed upon one end a stop or wheel engaging element 8 while its other end is beveled to form an inclined face 9 to permit a wheel of the car to readily roll upon the body into engagement with the stop 8. The 80 stop 8 is formed by extending the end of the body 7 and curving the same upwardly, rearwardly, and downwardly, and which presents a curved face 10 to the stop to conform to the periphery of the wheel. A 85 downwardly depending flange 11 is formed upon one edge of the body 7 to prevent said body from sliding laterally of the rails when placed thereon and is disposed against the inner face of said rails.

The end of the flange 11 that terminates with the beveled end 9 of the body is disposed on an incline as illustrated at 12 so as not to interfere with the wheel rolling 90 onto said body.

An L-shaped flange 14 is formed upon one edge of the stop to engage the outer side face of the car wheel and a flange 15

is formed upon the opposite edge of the stop to receive and engage the wheel flange of the car wheel and the inner face of said car wheel. The flange 15 is provided with 5 a pocket or groove 16 that receives the flange of the car wheel, thus it will be seen that the flanges 14 and 15 coöperate with each other in preventing the wheel of the car from shifting laterally in either direction on 10 the body 7.

A wedge-shaped member 17 is formed integrally with the stop 8 and projects forwardly of the shoe for the purpose of removing any obstacle that may be on the 15 rails of the track.

From the foregoing description taken in connection with the accompanying drawings, it will be noted that a braking device has been provided which can be readily and conveniently applied to a pair of wheels of a car and to the rails of a track so that said wheels are held against rotation and away from engagement with the rails, thereby obviating any danger of the wheels becoming flat or 20 worn and also obviating the use of employing the ordinary brakes on a car when descending a steep hill or by locking the wheels in other heretofore known manners which have proven very unsatisfactory 25 owing to the great amount of wear on the wheels as they slide along the rails.

While I have shown and described the preferred embodiment of my invention, it will be understood that minor changes in 30 construction, combination, and arrangement

of parts, may be made without departing from the spirit and scope of the invention as claimed.

Having thus described my invention, what I claim is:—

1. A braking device comprising a pair of shoes adapted to be positioned on the rails of a track with the wheels of a car thereon, stops formed on said shoes for engagement with the periphery of the wheels, means on 45 said stops for preventing lateral movement of the wheels in relation to the shoes, guiding means formed on the shoes for engagement with the rails, and wedge-shaped elements carried by the stops for removing obstacles from the rails.

2. A brake shoe comprising a body having one end tapered, a stop formed on the other end of said body and having a curved face to engage the periphery of the car wheels, 55 a flange formed on said body and adapted to engage the side face of a rail, an L-shaped flange formed on said stops and adapted to engage one side face of the car wheels, a flange formed on the other edge of the stops 60 and having a recess to receive the flange of the car wheel and also to engage the other face of the car wheels.

In testimony whereof I affix my signature in presence of two witnesses.

WILLIAM B. SPROUL.
